UNITED STATES PATENT OFFICE.

ARTHUR H. MERRILL, OF CROMWELL, CONNECTICUT.

DESIGN FOR A CLOCK-CASE.

SPECIFICATION forming part of Design No. 15,161, dated July 22, 1884.

Application filed June 12, 1884. Term of patent 7 years.

To all whom it may concern:

Be it known that I, ARTHUR H. MERRILL, of Cromwell, in the county of Middlesex and State of Connecticut, have invented a new Design for a Clock-Case; and I do hereby declare the following, when taken in connection with accompanying drawing and the letters of reference marked thereon, to be a full, clear, and exact description of the same, and which said drawing constitutes part of this specification, and represents a perspective view.

This design relates to a clock-case; and it consists in the configuration and ornamentation, as shown in the accompanying illustration, and hereinafter described. The base is in the shape of a parallelogram, the corners rounded. Around the base is a representation of a band of reeded work. From the upper edge the base is curved upward and inward, and from the top of this curved surface the body of the case rises. The body represents a plain square column at each angle, connected by a band of reeded work at the bottom, around the top a similar band of reeded work,

the band at the top and bottom, with the columns, forming a frame, which is filled by a panel, all as shown in the accompanying illustration.

The ornaments shown on the top of the clock may be omitted altogether or varied without departing from the general design, the essential features of which relate only to the base and body.

I claim—

The herein-described design for a clock-case, consisting of the base representing a reeded band, the base curved upward and inward from the top of the band to the body of the case, the body representing a plain square column at each angle, a band of reeded work connecting the columns at the base, and surrounded by a band of reeded work, as shown in the accompanying illustration.

ARTHUR H. MERRILL.
